UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A HEATING UNIT FOR ELECTRIC RADIATORS.

54,350.

Specification for Design.

Patented Dec. 30, 1919.

Application filed June 6, 1919. Serial No. 302,355. Term of patent 14 years.

To all whom it may concern:

Be it known that I, JOSEPH F. LAMB, a citizen of the United States, and a resident of New Britain, in the county of Hartford, State of Connecticut, have invented a new, original, and ornamental Design for a Heating Unit for Electric Radiators, of which the following is a specification, reference being had to the accompanying drawings, forming part thereof.

In the drawings—

Figure 1 is a view in side elevation showing my new design.

Fig. 2 is a front end view of said design.

I claim:

The ornamental design for a heating unit for electric radiators as shown.

JOSEPH F. LAMB.
